DESIGN FOR A DISPLAY STAND FOR SWIMMING TRUNKS OR THE LIKE

Findley Williams, Park Ridge, Ill., assignor to W. L. Stensgaard & Associates, Inc., a corporation of Illinois

Application April 24, 1940, Serial No. 91,921

Term of patent 14 years

To all whom it may concern:

Be it known that I, Findley Williams, a citizen of the United States residing at Park Ridge, in the county of Cook and State of Illinois, have invented a new, original, and ornamental Design for a Display Stand for Swimming Trunks or the like, of which the following is a specification, reference being had to the accompanying drawing, forming part thereof.

Figure 1 is a front perspective view of a display stand, for swimming trunks or the like, showing my new design; and Figure 2 is a rear perspective view thereof.

I claim:

The ornamental design for a display stand for swimming trunks or the like, as shown.

FINDLEY WILLIAMS.
